(57) **CLAIM**

What is claimed is the ornamental design for a toilet seat and lid assembly, as shown.

DESCRIPTION

FIG. 1 is a front perspective view of the toilet seat and lid assembly with the lid lifted 45 degrees;

FIG. 2 is a back perspective view of the toilet seat and lid assembly with the lid lifted 45 degrees;

FIG. 3 is a front perspective view of the toilet seat and lid assembly with the lid in the down position;

FIG. 4 is a back perspective view of the toilet seat and lid assembly with the lid in the down position;

FIG. 5 is a front view of the toilet seat and lid assembly with the lid lifted 45 degrees;

FIG. 6 is a back view of the toilet seat and lid assembly with the lid lifted 45 degrees;

FIG. 7 is a top view of the toilet seat and lid assembly with the lid lifted 45 degrees;

FIG. 8 is a bottom view of the toilet seat and lid assembly with the lid lifted 45 degrees;

FIG. 9 is a right side view of the toilet seat and lid assembly with the lid lifted 45 degrees;

FIG. 10 is a left side view of the toilet seat and lid assembly with the lid lifted 45 degrees;

FIG. 11 is a front view of the toilet seat and lid assembly with the lid in the down position;

FIG. 12 is a back view of the toilet seat and lid assembly with the lid in the down position;

FIG. 13 is a bottom view of the toilet seat and lid assembly with the lid in the down position;

FIG. 14 is a top view of the toilet seat and lid assembly with the lid in the down position;

FIG. 15 is a right side view of the toilet seat and lid assembly with the lid in the down position; and,

FIG. 16 is a left side view of the toilet seat and lid assembly with the lid in the down position.
